UNITED STATES PATENT OFFICE

GEORGE L. WILSON, OF DULUTH, MINNESOTA

CASTING MACHINE

Application filed May 31, 1928. Serial No. 281,882.

This invention relates to casting machines and has special reference to one particularly adapted for use by dentists or those of similar profession in making more or less delicate gold castings or the like.

The principal object is to produce an improved type of centrifugal casting machine that will force the molten metal of which the casting is to be made into the mold as spontaneously as possible with the desired molten state of the metal.

Another object is to produce such a machine having simple means whereby the desired initial thrust may be most delicately varied to suit specific requirements.

Other objects and advantages of the invention will appear in the further description thereof.

Referring now to the accompanying drawing, forming part of this application, and wherein like reference characters indicate like parts:

Figure 1 is a side elevation of one embodiment of my improved casting machine as applied to an electric power unit;

Figure 2 is a side elevation opposite to that shown in Figure 1 of the crucible and its carriage;

Figure 3 is an enlarged side elevation of the improved form of throwout switch;

Figure 4 is a perspective view of the crucible;

Figure 5 is a wiring diagram of the electric circuit of the device.

1 represents the housing of any suitable form of electric motor, the armature shaft 2 of which is made to extend vertically through the axis of the housing, and upon which just above the housing is mounted in any desired manner but fixed to the armature shaft 2 the balance wheel 3, preferably provided with an upstanding hub 4, and for conveniences hereinafter apparent I choose to provide the same with a knurled surface as at 5. The armature shaft is made to extend upwardly beyond the hub 4 and is externally screw threaded as at 6. Upon this screw threaded portion is screw threadedly mounted the cross-arm or beam 7, it being provided with a frusto-conically shaped hub portion 8, surmounted by a fric-

tion cap 9 and provided with a suitable oil cup 10, so that as the beam is threaded onto the armature shaft it may extend entirely through the hub portion 8 without in any way interfering with the action of the machine or the convenient lubrication thereof.

The cross-arm or beam 7 extends equally in either direction from the hub portion and one extremity is provided with the fixed upright end plate 11 for engagement with one end of the mold ring 12 when the latter is set in between the horizontally reciprocable adjustable crucible carriage 13; the latter being provided with a head 14 having concentrically arranged stepped portions 15 on the face 65 thereof for registration with the end of the mold ring common to the profession, said carriage being made readily slidable upon one end of the beam 7.

Upon the carriage 13 and back of the head 70 14 is a comparatively small platform 16, the rear portion of which is adjustable as desired vertically by a suitable screw bolt 17, and the entire carriage being readily slidable to any desired point on the arm by means of the set 75 screw 18, impingeable against the lower edge of the arm 7.

Upon the opposite end of the arm 7 is mounted the slideable counterweight 19 held thereupon by means of a suitable thumb screw 80 20 and adjustable longitudinally of the arm so as to counterbalance the crucible carriage and mold upon the opposite end; its functioning being obvious.

To one side of the motor housing 1 I have 85 fixed a bracket 21 which supports upon the horizontal platform 22 thereof the automatic cutout switch, comprising the block 23 which is bifurcated in its uppermost right hand corner as viewed in Figure 3 of the drawing, and in which cutout portion is pivotally mounted as at 24 the lever 25; it being squared in its lowermost end as at 26 and held between the two spaced insulated plates 27, they snugly filling the cutout portion of the block, and 90 a unitary portion thereof extending above the block. Upon this uppermost extension of the insulating block is mounted the conductor bridge 28 which surrounds said extension upon two sides and terminates forwardly therecf 100

in the converging spaced free ends 29 which are slightly inclined downwardly and their extreme ends 30 made to diverge abruptly for purposes hereinafter described.

5 By this construction the free ends of the conductor bridle are in constant engagement with the cylindrical enlargement indicated at 31 of the lever 25 when the latter is in its upright position and forming electric contact therewith; one terminal of the circuit indicated at 32 being connected to the bridle as at 33, while the other terminal 34 of the motor operating circuit is connected as at 35 to the half bridle 36 which is attached to 10 the unitary portion of the insulating material below the bridle 28 and spaced therefrom as well as spaced from the block 23. This half bridle terminates at its forward end in an L-shaped downward extension 37 bent outwardly away from the block, normally with 15 its free end in contact with the shaft 24 forming the pivotal connection of the lever 25, so that when this lever is in its upright position or in any way engaged by the bridle 20 25 the motor circuit is complete in respect to the cutout switch.

The upper portion of the lever 25 is somewhat enlarged as at 38 and insulated, it extending sufficiently far to at all times when 20 in upright position be in the path of the arm 7. Thus when sufficient power is applied to the cross arm in its attempt to follow the rotation of the armature shaft and force the lever to an inclined position as shown in 25 dotted lines, Figure 3, it will still maintain its contact with the free ends 29 of the bridle 28 until such time as it passes the abrupt angle formed by the diverging ends thereof when their inward spring action will further expel 40 the lever, thereby opening the circuit; it being understood that this is a bypass circuit in the main motor operating circuit which latter is controlled by a suitable momentary switch such as indicated at 39.

45 The crucible 40 is of the common type, except that one side thereof indicated at 41 is brought up to an abnormal extent over the basin therein and the latter is formed slightly to one side of the axis of the discharge 50 opening of the crucible, said inclination being in the direction of the travel of the supporting arm so that the initial movement of the arm would have a more direct thrust towards the discharge opening into the mold 55 and whereby any possible splashing or spilling of the molten metal is overcome.

As before stated the normal tendency of the arm 25 when placed upright is to there remain, and this tendency is sufficient to hold 60 the cross arm (the counterweighted end of which is supposed to engage same just prior to making a casting) against movement with the initial rotation of the armature 6. As the motion of the latter continues resulting in 65 the screwing down of the cross arm there-

upon until the lower face of the hub 8 engages the face of the hub 4 of the balance wheel, or rather the cushion washer 42 thereupon, the cross-arm will instantly follow at the attained speed of the motor and power to the 70 motor will continue so long as the lever 25 is in engagement with the extensions of the bridle 28; this being purposely designed so that such power may continue for the fraction of a second to hold the motor at such 75 attained speed, and carry with it the armature and its load. However it will be understood that the rotative action of the arm 7 will instantly force the arm 25 to an inclined position as the arm 7 passes over the free end 80 of same, and thus break the electric circuit to the motor though somewhat gradually as previously described by the drag of the arm 25 through the inclined portions of the bridle.

85 From the foregoing it is apparent that the motor after being started by pushing the impulse switch 39 will attain full speed prior to the screwing down of the arm 7 to the balance wheel 5 and which latter provides the necessary augmented force to instantly grab said crucible carrying arm and rotate it immediately at the attained speed of the motor, thus providing the all essential centrifugal thrust to the molten metal in forcing it into the more 90 minute intricacies of the mold in which the casting is formed.

95 The use of this machine has further demonstrated the fact that but a fraction more than the actual amount of material for forming the casting is ample, whereas with the common centrifugal casting machine a much larger surplus of material is necessary, invariably forming what is known as a "button" at the entrance of the gate to the mold, 100 and as is known to those versed in the art repeated melting of metal such as gold or the like is detrimental.

105 It is to be understood that modifications of the embodiment here illustrated may be resorted to, and that the invention may be employed in a machine driven by other power than electricity.

110 Having thus described my invention, what I claim and desire to secure by Letters Patent, is:

115 1. A dental casting machine comprising a power unit, means operated by the initial movement of the power unit, mold and crucible carrying means upon said last mentioned means, and means whereby the mold and crucible means is operated by and subsequent to the initial action of the power unit.

120 2. A dental casting machine comprising a power unit, centrifugal mold and crucible carrying means operable by the power unit, and means whereby the mold and crucible means is operated subsequent to the initial 125 action of the power unit.

125 3. A dental casting machine comprising a 130

power unit, centrifugal mold and crucible carrying means operable by the power unit, means for starting the power unit, and means whereby when the power unit attains sufficient speed it will operate said first mentioned means immediately at the attained speed of the power unit.

4. A machine of the type described comprising an upright shaft the upper extremity of which is screw threaded, means for rotating said shaft, a cross arm mounted upon said shaft, crucible and mold carrying means upon one end of the cross arm and an adjustable counterbalance upon the other end, and automatic means whereby initial rotation of the shaft is accomplished for a predetermined time prior to affecting the cross arm and substantially simultaneously stopping the shaft.

5. A casting machine of the class described including a motor, a manually operable starting switch therefor, counterbalanced crucible and mold supporting means mounted upon the armature of the motor and operable thereby, and an automatically operated switch operable by the action of the crucible and mold supporting means.

6. A casting machine of the class described including a motor, a manually operable momentary switch for starting the motor, crucible and mold supporting means carried by the motor armature, and a cutout switch automatically operable by the action of the crucible and mold supporting means irrespective of the action of the momentary switch.

In testimony whereof I affix my signature.
GEORGE L. WILSON.
